HANDLE REENFORCING CUP

Elmer R. Krueger, Indianapolis, Ind.

Application November 10, 1932, Serial No. 641,989

5 Claims. (Cl. 229—52)

This invention relates to a unitary handle per cup.

The chief object of this invention is to provide a handle cup which is so arranged that the cup body may be of relatively light material and which is reenforced by the handle forming structure and whereby the handle may be of relatively light material and the parts forming the same so associated that the requisite handle strength is provided and that the junction of the handle and the cup is of such character that the ordinary shearing or tearing stress of the handle forming stock projecting from the cup due to the weight of its contents and the cup is insufficient to tear the handle from the cup.

The chief feature of the invention consists in the provision of a cup provided with a peripheral band secured in peripheral arrangement to the cup and portions of said band projecting from the cup to form a handle and being secured together for increasing the stock and strength of the handle.

Another feature of the invention consists in the formation of the band as a single strip and the association of the free ends of the strip together as the handle portion.

Another feature of the invention consists in the formation of the handle from a straight strip and its association with a conical cup, whereby the handle forming strip is arranged in biased relation relative to the exterior of the cup so that the separating strain in the strip is angular to the handle portion of the strip and the biased positioning of the strip is such that the side wall of the cup near the bottom is reenforced by said strip and the side portion of the cup diagonally opposite and near the top is reenforced by the same strip.

The full nature of the invention will be understood from the accompanying drawing and the following specification and claims:—

In the drawing, Fig. 1 is a side elevation of the completed article constituting the handle of the cup.

Fig. 2 is a bottom plan view thereof.

Fig. 3 is an enlarged plan view of a straight strip adapted to form the biased reenforcing band when applied to a conical cup and the handle portion for said cup.

In the drawing, 10 indicates the side wall of a conical cup and 11 the bottom thereof. The cup may or may not be provided with a lip. Herein the lip is shown omitted. There is provided a straight strip 13 of the desired length and having, if desired, a scored connection 14 at each end with

an end flap 12. The scoring 14 is biased relative to a longitudinal element of the strip.

The ends of the flaps are suitably formed and include an inclined edge 15, an arcuate intermediate edge 16, an inclined straight edge 17 and the edge 18 which in alignment with the bottom of the strip, the bottom edge being indicated by the numeral 20. The top edge of the strip is indicated by the numeral 21.

When applied to a conical cup, the strip is arranged to peripherally envelope the same and exteriorly, and is provided peripherally with adhesive on the entire inner surface of the strip so that the strip is adhesively secured substantially throughout its entire area which is in contact with the cup.

When the straight strip is applied to a conical cup, it is positioned on the cup, in biased relation and the biasing is such that the lower edge 20 of the strip is positioned adjacent the bottom 11 of the cup while the upper edge 21 of the strip is positioned near the top 9 of the cup and at diametrically opposite points, as shown in Fig. 1. The strip after being adhesively secured to the cup is folded along the score lines 14 or substantially coincident therewith, if no scoring is provided, and upon its application to the cup so that the two portions 12 are adhesively secured together, back to back, to form a single handle of double width near the top of the cup and diagonally opposite the application of the strip to the side wall near the bottom of the cup.

This type of support constitutes a reenforcement for the cup per se, and also insures that the weight of the cup and its contents are transmitted to the handle in lines that are longitudinal with respect to the strip and, therefore, angular or biased with respect to the scoring 14. So that, the strength of the connection between the handle and the band is materially greater than if the back or strip were of arcuate formation and the curvature such that the band encircled the cup in a non-biasing relation.

The use of the band entirely and peripherally encircling the cup permits the employment of a relatively light weight cup which will have all the strength and rigidity as well as every other advantage of a very heavy cup.

The scoring or equivalent bending, either pre-formed or formed, by the securing of the band to the cup provides a handle of relatively great rigidity and strength but flexibly or hingedly associated with the cup.

As an ornamental feature, the strip may be of different color than the cup.

It is to be noted that when applied to a conical cup, the straight strip has its edges 15 of the handle lying in the plane of the top of the cup or the same would lie parallel thereto and that the edges 17 or back of the handle are inclined similar to the alignment of the cup but at a slightly steeper angle and that the bottom edges 18, while in alignment with the bottom of the strip 20, are inclined downwardly but at a materially less angle than the edges 17 when mounted on the cup. So there results a handle upon the cup which is not ornamentally objectionable in appearance.

The band may be formed in a manner other than that set forth herein before and then applied to the cup, and in that event, the cup would be telescoped in the band and the band would be sealed on to the cup and the handle simultaneously formed in the sealing operation.

The invention claimed is:—

- 20 1. A handle cup including a conical cup body and an exterior encircling band terminating in a radially projecting handle, the band portion being peripherally secured to the body in biased relation thereabout.
- 25 2. A handle cup including a conical cup body and a handle projecting radially therefrom, com-

prising a single strip, peripherally secured to the cup body in biased relation thereabout, the free ends of said strip projecting from the body adjacent each other and being secured together to form a handle of double strength.

3. A handle cup including a cup body and an exterior encircling band terminating in a radially projecting handle, the band portion being peripherally secured to the body in biased relation thereabout.

4. A handle cup including a cup body and a handle projecting radially therefrom, comprising a single strip, peripherally secured to the cup body in biased relation thereabout, the free ends of said strip projecting from the body adjacent each other and being secured together to form a handle of double strength.

5. A handle cup including a conical cup body and an exterior encircling band terminating in a radially projecting handle, said band being formed from a straight strip and being secured in biased relation to the cup body with the surplus portion of the band forming a radially projecting handle of double strength.
